Primary Examiner — Vy N Koenig(74) *Attorney, Agent, or Firm* — Rosenberg, Klein & Lee(57) **CLAIM**

The ornamental design for a “protective sleeve for food service wrap dispensing cartons,” as shown and described.

DESCRIPTION

FIG. 1 is a perspective view of a protective sleeve for food service wrap dispensing cartons showing my new design; FIG. 2 is front elevation view thereof; FIG. 3 is a rear elevation view thereof; FIG. 4 is a right side elevation view thereof; FIG. 5 is a left side elevation view thereof; FIG. 6 is a top plan view thereof; FIG. 7 is a bottom plan view thereof; and, FIG. 8 is a perspective view thereof in an exemplary environment. The broken lines shown are included for the purpose of illustrating unclaimed portions and environment of the protective sleeve for food service wrap dispensing cartons that form no part of the claim.
